METHOD OF AND MEANS FOR OPERATING
BOILERS OF CERTAIN TYPES

Thomas E. Murray, Jr., Brooklyn, N. Y.

Application October 27, 1936, Serial No. 107,754

10 Claims. (Cl. 122—367)

In a patent of Thomas E. Murray, No. 2,029,437 of February 4, 1936, there are described water walls for boilers, superheaters and similar heat exchangers made up of or lined with upright tubes, spaced apart and provided with metal extensions into the spaces between them of such length and spacing as to form with the tubes a substantially or approximately complete metal wall. In practice it has been found impossible 5 or difficult to maintain such extensions of the considerable length which is desired. Various schemes have been proposed and tried for accomplishing this purpose, such as the making or coating of the extensions with resistant metal 10 and the use of extensions of special shapes. In a later application, Ser. No. 66,412, filed by myself February 29, 1936, I have described a unit to be used in such walls and a method of operation of boilers or the like having such walls, in 15 which the metal extensions are maintained by replacing the outer portions thereof from time to time as they burn off. The accompanying application is in large part a continuation of the aforesaid application. The accompanying drawing 20 illustrates embodiments of the invention.

Fig. 1 is a horizontal section of a boiler wall; Fig. 2 is a front elevation of a portion of the same; Fig. 3 is a horizontal section through one of the tubular units; Fig. 4 is a section on the line 4—4 25 of Fig. 3; Fig. 5 illustrates a modification in horizontal section; Fig. 6 is an end view of the pin or extension of Fig. 5; Fig. 7 is a view similar to Fig. 2 illustrating a modification.

The boiler wall of Fig. 1 is made up of a metal shell 10, an outer structure of plastic material, such as a heat insulating coating 11 and fire bricks 12 and 12^a, or other refractory. On the inner face, that is the face exposed to the fire, is a lining made up of tubular units each comprising 30 a tube 13 with pins or projections 14 at diametrically opposite points and projecting into the spaces between the tubes.

In accordance with the prior patent and application referred to, the spacing and size of the 35 projections on each tube are determined in order that, while constituting in effect an approximately continuous metal wall, they are sufficiently separated to avoid actual contact and to permit of their separate welding to the tube without inducing in them such internal stresses as 40 would weaken their resistance to oxidation and burning off at the ends under the high temperatures contemplated. This is to fit them for the severest usage, as in the walls of boiler furnaces heated by pulverized coal or other fuel burned in

suspension, such as oil and gas. With powdered coal, there is a natural tendency to accumulate a coating of refractory ash which though it falls off at times quickly renews itself. And it has been proposed to initially apply a permanent 5 coating of refractory material over the whole metal surface.

In any case, whether the extension be a continuous flange or a succession of closely spaced pins and whether or not they be shielded by a 10 refractory coating, the ends farthest from the tubes tend to burn off under the conditions encountered in modern high temperature installation. When the burning off occurs the projections perform less perfectly the functions for 15 which they were designed. It is the purpose of the present invention to maintain the original dimensions of such projections on all sorts of tubular heat exchangers which are exposed in use to the burning off of the ends.

The parts farthest removed from the tube experience the least cooling effect from the water, steam, or other fluid therein and tend to burn off progressively until there is a balance between the external heat and the internal cooling effect. 20 But, for some installations, such as high powered boiler furnaces it is desirable to have the projections extending beyond this balanced point.

By operating in accordance with the present invention, it is possible to build the walls with 30 projections extending beyond the balanced point, that is, beyond the limit which was previously thought available; and this result can be achieved with projections made of ordinary grades of steel, like that of the ordinary boiler tubing, for example. Making them of materials or shapes having a longer life under the conditions encountered 35 is not necessary, though such expedients may have the additional advantage of requiring less frequent repairs or replacements.

According to Figs. 3 and 4, the tube 13 has the extensions 14 in the form of small tubes each welded by a resistance weld 15 to the main tube 13. Or other kinds of weld may be used. Or the projection 14 may be a solid pin except for a hollow at its outer end. The outer end of the pin initially comprises a replaceable end piece 16 having on one face a central projection 17 fitting within the bore of the pin 14. The end piece 16 may be of more highly resistant material than 40 the body of the pin 14. For example, the latter may be of ordinary low carbon steel similar to that of the boiler tube 13 and the end piece of stainless or other nickel-chrome steel alloy. When the first end piece 16 burns nearly off, the 45 50 55

stub of it can be removed and replaced by a new whole one, restoring the pin to its original length. The extent of the end piece 16 should be sufficient to permit the necessary manipulation, but 5 no greater. It may be fastened to the end of the pin by welding or in any other way.

Fig. 5 shows a solid pin 14^a with an end piece 16^a having a flange 17^a fitting around the end of the pin. This is used in the same way as the arrangement of Figs. 3 and 4.

It is not essential to have the end portion separate from the body portion of the projections. With modern methods of welding, and particularly with portable welders, it is possible to add 15 metal at the ends of the projections whether such ends be in the form of replaceable caps or blocks, or be integral originally.

For example, in Fig. 7 the tubes 13 are provided with pins 18 which are initially integral from 20 end to end. When they burn off their lengths may be shortened, for example, along the irregular dotted line 19. After this burning away has become sufficient to make a fairly wide opening between the ends of the pins that originally 25 spanned the space between the two tubes, the flames have a better access to the ends and the backs of the pins than originally and the burning effect is to that extent intensified. The wall back of the pins also loses its original substantially complete protection and burns away at an increasing rate. The shortening of the pins also diminishes the area of metal exposed to the fire and transmitting the heat thereof to the tubes and to the water within the tubes causes a 30 diminution of the efficiency of the boiler and the speed with which it generates steam.

I propose to keep these objectionable tendencies within substantially the original limit by adding metal to the ends of the pins from time 40 to time so as to maintain their extension over practically the entire width of the spaces between adjacent tubes. This may be done by squaring off the ends of the pins and welding previously shaped pieces thereon similar to the caps of Fig. 45 5, for example, or identical in diameter with the original pin, or by depositing and building up metal by means of known types of electric arc welding machines. Such an operation is easily performed. It is not essential to maintain the 50 extent or shape of the original cross-section. In fact the ends may be enlarged and may even be united to the ends of the adjacent pins on the same tube or on the next tube in this repair operation without substantial objection.

55 In replacing the burned away portions of the projections they will generally be restored to substantially their original extent. The restored projections, however, may have a greater or less extent than the original and may offer an increased or reduced area of exposure to the fire.

Various other modifications in detail may be made by those skilled in the art without departing from the invention as defined in the following claims.

65 What I claim is:

1. The method of operating a boiler or the like

having a wall comprising tubes spaced apart with projections extending into spaces between them and exposed to high temperatures, which method comprises adding metal to the outer end portions of said projections from time to time as they are burned off so as to maintain them of a determined extent. 5

2. The method of operating a boiler or the like having a wall comprising tubes spaced apart with projections extending into the spaces between them and exposed to high temperatures, which method comprises adding preformed metal extensions to the outer end portions from time to time of said projections as they are burned off so as to maintain them of a determined extent. 10 15

3. The method of operating a boiler or the like having a wall comprising tubes spaced apart with projections extending into spaces between them and exposed to high temperatures, which method comprises extending said projections 20 from time to time as they burn off so as to maintain them of an extent to substantially cover the width of the space between the tubes and to provide an approximately continuous metal wall between the fire and the outer portion of the 25 structure.

4. A unit of the character described comprising a tube for circulating a fluid and projections extending outward from said tube adapted to be exposed to high temperatures and to conduct 30 heat to the tube and the fluid therein, said projections having outer end portions which are replaceable when burned off.

5. A unit for use in boiler furnace walls comprising a tube having along diametrically opposite lines a series of small closely spaced projections extending outward therefrom, said projections having end pieces which are separate from the bodies of the projections and are replaceable when burned off. 35 40

6. The unit of claim 4, said outer end portions being of material more resistant to oxidation at high temperatures than the body portion of the projections.

7. The unit of claim 4, the body portion and 45 the end portion of the projections fitting one within the other.

8. The unit of claim 4, the body portion and the end portion of the projections being welded together. 50

9. A unit of the character described comprising a tube for circulating a fluid and projections extending outward from the tube adapted to be exposed to high temperatures and to conduct heat to the tube and the fluid therein, said projections 55 being hollow and having separate outer end portions fitting within the hollow space in the projections.

10. A unit of the character described comprising a tube for circulating a fluid and a series of 60 small closely spaced projections extending outward from the tube along diametrically opposite lines adapted to be exposed to high temperatures and to conduct heat to the tube and the fluid therein, said projections being hollow. 65
